UNITED STATES PATENT OFFICE

OSCAR JUNGGREN, OF SCHENECTADY, NEW YORK, ASSIGNOR TO GENERAL ELECTRIC COMPANY, A CORPORATION OF NEW YORK

ELASTIC FLUID TURBINE

Application filed April 12, 1928. Serial No. 269,449.

In the case of large turbines where for any reason it becomes desirable not to build the entire machine into a single casing, it is known to build the turbine in two or more sections having separate casings. For example, such a turbine may comprise a high pressure section and one or more low pressure sections, the high pressure section being connected in series with the low pressure section or sections as regards the flow of elastic fluid, and each section driving its own generator. Such arrangements are quite satisfactory, but are open to the objection that they occupy an increased amount of floor space, a consideration which in some instances is a matter of great importance.

The object of my invention is to provide an improved construction and arrangement in a turbine comprising a high pressure section and one or more low pressure sections driving separate generators or other driven machines which is very economical in floor space and permits large powers at comparatively high speed.

For a consideration of what I believe to be novel and my invention, attention is directed to the following description and the claims appended thereto.

In the drawing Fig. 1 is a side elevation of a structure embodying my invention, and Fig. 2 is an end view thereof.

According to one embodiment of my invention, I mount the low pressure turbine section and the machine driven thereby on a suitable bed plate in the usual manner, and I then mount the high pressure turbine section and its driven machine directly on top of the low pressure turbine section and its driven machine. Preferably the arrangement is such that the exhaust end of the high pressure section stands directly adjacent to the admission opening of the low pressure section so that the connection for conveying the exhaust elastic fluid from the high pressure section to the low pressure section may be comparatively short. The generators may be housed in a single casing or in separate casings as is found to be desirable. Preferably, however, I house them in a single casing, the

two generators thus becoming, in a way, a unitary machine or structure.

Referring to the drawing, 1 indicates a low pressure turbine section, the casing of which is provided with feet 2, by means of which it is supported on its foundation. In the present instance, a turbine structure of the double flow type is illustrated, the steam entering an admission opening 3 and flowing in opposite directions through righthand and lefthand sections 4 and 5 to the exhaust opening 6. The exhaust opening 6 will be connected to a condenser in the usual manner. The condenser is not illustrated in the drawing as it forms no part of the present invention. 7 indicates the shaft of the low pressure turbine section and 8 indicates a generator rotor driven thereby. The low pressure turbine section is illustrated only in outline as its specific construction forms no part of the present invention. It may be a suitable turbine of either the impulse or reaction type.

9 indicates a high pressure turbine section mounted directly over low pressure turbine section 1 and supported directly thereon. At its low pressure end, high pressure turbine section 9 is supported by a bearing pedestal 10 which rests on the upper ends of supports 10^a formed integral with the upper half of the casing of turbine section 1. At its high pressure end turbine section 9 is supported by a bearing pedestal 11 which rests on the upper ends of supports 11^a carried by projecting feet or supports 12 which form a part of the casing for turbine section 1. Supports 11^a extend up on each side of shaft 7 and are tied together and made rigid by means of suitable cross-braces 13. The exhaust end of high pressure turbine section 9 is located directly over admission opening 3 and is connected to it by a suitable connection 14 of a character such as to permit relative expansion and contraction in a vertical direction. 15 and 16 indicate conduits through which high pressure elastic fluid is supplied to the high pressure turbine section 9. They are located one on each side of the high pressure turbine section and communicate with valve chests 17 and 18 containing valves of any suitable type,

for example such as that shown in the patent to Dryer 1,471,316, dated October 16, 1923, to control the admission of elastic fluid to the turbine. In the present instance a known type is illustrated, the same being opened and closed by suitable cams on cam shafts 19 and 20 connected by gearing to a cross-bar 21 which is turned in the usual way through a rack and gear 22 operated by means of a servo motor 23. In the outline, 24 indicates the 10 governor for the turbine sections. The valve gear may be operated from it in any suitable manner. The details of the valve actuating means is not illustrated as it forms no part 15 of the present invention. Valve chests 17 and 18 are preferably supported by means of suitable spring supports 25. This arrangement serves to leave the valve chest free to expand and contract.

20 The bearings at the turbine end of the generators are shown as being carried by pedestals 26 which in turn are supported from flanges 27 formed integral with the casing of turbine section 1. The bearings at the other 25 end of the generators are carried by pedestals 28 which may be supported from a bed plate in any suitable manner. 29 indicates the rotor of the generator driven by high pressure turbine section 9 and 30 indicates the 30 shaft of turbine section 9. The field work of the generators may be built as a unitary field structure, and housed in a single housing 31. This serves to give a rigid generator structure and one economical to build.

35 With the foregoing arrangement, it will be seen that I provide a turbine structure comprising a high pressure section and a low pressure section which occupies a minimum amount of floor space and one wherein the high pressure section discharges elastic fluid 40 directly to the low pressure section through a very short conduit. This latter is of substantial importance in that it avoids the use of large piping between the two units.

45 In accordance with the provisions of the patent statutes I have described the principle of operation of my invention together with the apparatus which I now consider to represent the best embodiment thereof; but I desire 50 to have it understood that the apparatus shown is only illustrative and that the invention may be carried out by other means.

What I claim as new and desire to secure by Letters Patent of the United States 55 is:

1. In combination, a double flow low pressure turbine section having a centrally located inlet opening, supporting feet carried by the casing of said low pressure section, 60 vertically extending members carried by said supporting feet, and a high pressure turbine section mounted on said vertically extending members and having its exhaust opening connected to the inlet opening of the low pressure turbine section.

2. In a unitary structure, a low pressure set comprising a low pressure turbine having a horizontal shaft and a driven machine in axial alignment with and driven by the low pressure turbine, the casing of said low pressure turbine being provided with supporting means at its two ends, and a high pressure set comprising a high pressure turbine having a horizontal shaft and a driven machine in axial alignment with and driven by the high pressure turbine, said high pressure turbine being mounted on said supporting means directly above the low pressure turbine and said second named driven machine being mounted above and supported on the first named driven machine.

3. In combination, a double flow low pressure turbine having a downwardly facing exhaust opening and a centrally located inlet opening, supporting means carried by the casing of the low pressure turbine at its two ends, and a high pressure turbine mounted directly above the low pressure turbine on said supporting means.

4. In combination, a low pressure turbine section having an inlet opening, supporting feet carried by the casing of said low pressure section, vertically extending members carried by said supporting feet, and a high pressure turbine section mounted on said vertically extending members and having its exhaust opening connected to the inlet opening of the low pressure turbine section.

5. In combination, a double flow low pressure turbine having an exhaust opening and a centrally located inlet opening, supporting means carried by the casing of the low pressure turbine at its two ends, and a high pressure turbine mounted directly above the low pressure turbine on said supporting means.

6. In combination, a low pressure turbine having an exhaust opening and an inlet opening, feet carried by the casing of the low pressure turbine for supporting it on a foundation, supporting means carried by the casing of the low pressure turbine at its two ends, and a high pressure turbine mounted directly above the low pressure turbine with its bearings supported on said supporting means.

7. In combination, a low pressure turbine section having a casing, supporting feet carried by the forward end of said casing and forming a part thereof, a high pressure turbine section which is mounted above the low pressure turbine section and exhausts into it, a vertically disposed structure which is supported at its lower ends by said feet and supports one bearing of said high pressure turbine section, and means supported by and forming a part of the low pressure turbine casing for supporting the other bearing of the high pressure turbine section.

8. In combination, a low pressure turbine section having a casing, supporting feet car-

ried by the forward end of said casing and forming a part thereof, a high pressure turbine section which is mounted above the low pressure turbine section and exhausts into it, a structure comprising vertically disposed members which are supported at their ends by said feet and a transversely extending member which connects said vertically disposed members for supporting one bearing of said high pressure turbine section, and means carried by the casing of the low pressure turbine section for supporting the other bearing of the high pressure turbine section.

10 9. In combination, a double flow low pressure turbine having an exhaust opening and a centrally located inlet opening, supporting means carried by the casing of the low pressure turbine at its two ends, a high pressure turbine mounted directly above the low pressure 15 turbine on said supporting means, a driven machine for the low pressure turbine, and a driven machine for the high pressure turbine supported on the first named driven machine.

20 25 25. In witness whereof I have hereunto set my hand this 11th day of April, 1928.

OSCAR JUNGGREN.
